UNITED STATES PATENT OFFICE.

GEORGE H. LELAND, OF DAYTON, OHIO, ASSIGNOR OF ONE-HALF TO THE LELAND ELECTRIC COMPANY, OF DAYTON, OHIO, A CORPORATION OF OHIO.

BRUSH-LIFTING DEVICE FOR ELECTRIC MOTORS.

Application filed March 18, 1926. Serial No. 95,579.

This invention relates to brush lifting devices for electric motors and more particularly to a combined brush lifting device and short circuiting device for use in connection with repulsion-induction motors.

One object of the invention is to provide a device which will be automatically moved into engagement with the brush to hold the same out of contact with the commutator.

10 A further object of the invention is to provide a device which will be automatically operated to engage the brush, move the same out of contact with the commutator, and hold the same in its inoperative position.

15 A further object of the invention is to provide an automatically actuated device having frictional contact with the brush to hold the same against movement toward the commutator.

20 A further object of the invention is to provide a repulsion-induction motor with a centrifugally controlled short circuiting device and a centrifugally controlled device for holding the brush in an inoperative position and having means for causing the two 25 centrifugally controlled devices to operate in unison.

A further object of the invention is to provide such a mechanism in which a single 30 yieldable device will act upon both centrifugally operated mechanisms.

Other objects of the invention will appear as the mechanism is described in detail.

In the accompanying drawings Fig. 1 is 35 a front elevation of a mechanism embodying my invention, partly in section, with the retaining plate removed, and showing the centrifugally operated mechanisms in their retracted positions; Fig. 2 is a section taken 40 on the line 2—2 of Fig. 1; Fig. 3 is a front elevation of the centrifugally operated mechanisms with the retaining plate removed and showing said mechanisms in their extended positions; Fig. 4 is a section taken on the 45 line 2—2 of Fig. 1 and showing the centrifugally operated mechanisms in their extended positions; Fig. 5 is a transverse sectional view taken on the line 5—5 of Fig. 4; Fig. 6 is a detail of one of the connecting plates; Fig. 7 is a sectional detail view of a modified 50 form of brush controlling device; Fig. 8 is a sectional detail view of another form of a brush lifting device; Fig. 9 is a sectional detail view of another form of brush controlling device; Fig. 10 is a sectional view

taken axially of the commutator and showing the brush controlling mechanism applied to the face of the commutator; and Fig. 11 is a sectional view showing a modified actuating mechanism for the brush lifting 60 device.

In these drawings I have illustrated one embodiment of my invention, together with certain modifications thereof but it will be understood that the various forms here 65 shown have been chosen for the purpose of illustration only and that the mechanism may take various forms and may be used either in whole or in part with commutators of various kinds.

70 In these drawings I have shown only the shaft and commutator of a motor, as the other parts of the motor have no direct bearing on the invention and are not necessary to its understanding. The commutator may 75 be of any suitable character and, as here shown, at 1, is of a conventional type and is rigidly secured to the motor shaft 2. The commutator comprises a circumferential series of contact bars 3 which are insulated 80 one from the other and from the body or core of the commutator. A repulsion-induction motor starts as a repulsion motor and operates as such until it has reached its normal or working speed, at which time the 85 commutator is automatically short circuited and the motor continues to operate as an induction motor so long as it maintains its normal speed. The short circuiting of the commutator is usually accomplished by 90

means of a centrifugally operated short circuiting device and there are various forms of short circuiting devices which may be used for this purpose. As shown in Figs. 1 to 4 the short circuiting device comprises 95 a series of contact members or weights 4 which are arranged circumferentially of the motor shaft 1 adjacent to the face of the commutator and are yieldably held in their retracted positions so that they may be 100 moved outwardly by centrifugal force into engagement with the contact bars of the commutator. The contact members are tapered toward the axis of the shaft so that they are substantially segmental in shape and 105 each is provided at its rear outer corner with a contact portion or nose 5 which bears against the face of the commutator and moves into engagement with the contact bars 3 of the commutator when the short circuit- 110

ing device is moved outwardly by centrifugal force, the commutator bars being provided with overhanging end portions 6 to limit the outward movement of the short circuiting element. The outer edges of the contact members 4 slope forwardly and inwardly and are preferably slightly curved to provide a seat for a circumferentially arranged contractile band 7, which is here shown in the form of an annular helical spring. This spring serves to retain the contact members normally in their innermost or retracted positions but will yield to permit the contact members to move outwardly by centrifugal force into engagement with the contact bars of the commutator when the motor has attained a predetermined speed. Mounted on the motor shaft 2, adjacent to the forward edges of the contact members 4 of the short circuiting element, is a plate or disk 8, the outer portion of which extends beyond the outer edges of the contact members and against which the helical spring 7 bears, the arrangement being such that the spring will resist the outward movement of the contact members and will also press the parts 5 thereof against the face of the commutator. If desired, this plate 8 may be provided with an obstruction, such as an annular bead or rib 9, so arranged that it will engage the outer side of the annular spring 7 when the short circuiting element is in its retracted position and will resist the outward movement of said spring, and consequently of the contact members, until the centrifugal force is sufficient to force the spring past the bead or obstruction 9. When the short circuiting element is in its extended or operative position the bead 9 will engage the inner side of the spring 7 and thus resist its inward movement until the centrifugal force has been so reduced that the tension of the spring will move past the bead. Thus the outward movement of the short circuiting element may be prevented until the motor has attained a relatively high speed and when this speed is attained the spring will be moved quickly across the bead 9 and the several contact members will move quickly and simultaneously into engagement with the commutator bars. Likewise the bead will resist the inward movement of the spring until the speed of the motor has been reduced considerably below the speed which was necessary to move the short circuiting element into its operative position. Consequently minor fluctuations of speed will not cause the short circuiting device to move to its inoperative position. As here shown, the several contact members are retained in substantially radial positions and held against lateral displacement by means of connecting plates 10 which are arranged between adjacent contact members at intervals about the

short circuiting element and which are provided with forwardly extending portions or lugs 11 which are slidably mounted in a guide or slot 12 in the disk or plate 8. In the present arrangement the connecting plates 10 are arranged in pairs and the plates of each pair have oppositely projecting circumferentially extending portions 13 which constitute supports for the adjacent contact members 4 and the ends of which are outwardly turned, as shown at 14, to retain the inner ends of the contact members in engagement therewith. If desired, the supporting portion 13 of the plate may have an outwardly extending projection or bead 15 which extends into correspondingly shaped recesses 16 in the inner edges of the contact members and permits of a pivotal movement thereof.

Mounted on a fixed part of the motor frame, not here shown, are the brush holders 17, their being in the present instance two of these brush holders spaced apart about the circumference of the commutator and electrically connected one to the other by a conductor bar 18. Each brush holder has a longitudinal guideway 19 extending lengthwise thereof and in which is mounted a brush 20, the brush being of a width slightly less than the width of the guideway. The central portion of the guideway is enlarged to receive a coiled spring 21 which is confined between the upper end of the brush and a fixed abutment at the outer end of the guideway, and serves to move the brush toward the commutator and to hold it yieldingly in engagement therewith. As here shown, the outer end of the guideway is closed by a disk 22 held in position by a plug 23 screw threaded into the end of the brush holder. The brush 20 is connected with the disk 17 by a flexible conductor 24 which will permit of its movement lengthwise of the guideway. Supported adjacent to the brush holder and arranged to enter the guideway 19 is a device adapted to engage the brush and hold the same against movement toward the commutator. This device may be of such a character that it will both grip the brush and lift the same away from the commutator and hold it in spaced relation to the commutator, or it may be of such a character that it will merely grip the brush and hold it against movement toward the commutator, without imparting outward movement thereto. In this latter case the contact of the periphery of the commutator with the brush will move the same outwardly, because in practice it is seldom that a commutator is perfectly circular in form but it will have a high spot or high spots on its periphery which will engage the brush and force the same outwardly, so that after a single rotation of the commutator the brush will engage only the high point

thereon, and the impact of this high point of the commutator with the brush will cause the brush to be moved further outward so that after a few rotations of the commutator the high point also will clear the brush. In that form of the device illustrated in Figs. 1 to 6 I have utilized a device which lifts the brush away from the commutator and holds the same in its lifted position. As there shown the brush holder 17 is provided in its front and rear walls with openings 25 in which are mounted clamping members or blocks 26 and 27, the clamping blocks being of such a character and so arranged that they may be moved into the side portions of the guideway 19 and will there engage the respective edges of the brush 20. Any suitable means may be employed for causing the operative movement of the clamping members but preferably this is accomplished by applying pressure to one clamping member and pressing the brush against the other clamping member, the last mentioned clamping member being yieldably held against movement. The clamping members are so mounted that when moved laterally in one direction they will also be moved outwardly away from the commutator. As here shown, each clamping member has an upwardly and rearwardly inclined slot 28 through which extends a pin 29, these pins being supported in the walls of the brush holder. Pivotally mounted adjacent to the brush holder is a lever 30 which, as here shown, comprises parallel side members arranged on opposite sides of the brush holder. In the present instance, these side members or levers are pivotally supported by the rear pin 29. The two members of the lever extend forwardly beyond the brush holder and are rigidly connected one to the other by a transverse bar 31. In the present construction, the two arms of the lever are provided with openings 32 to receive the ends of the forward pin 29, which project beyond the respective sides of the brush holder, these openings being of such a size that the pin will not interfere with the movement of the lever. A spring acts on the rear clamping member 27 to move the same forwardly and to cause it to act upon the brush 20 to move the latter in a forward direction. This spring may be of any suitable character but, in the present device, it is shown in the form of a loop spring 33, the rear portions of which are curved downwardly and connected by a transverse bar 34 which is seated in a recess 35 formed in a lug 36 projecting rearwardly from the clamping member 27. The forward ends of the two arms of the loop spring 33 are seated in the respective arms of the lever 30, the arrangement being such that the cross bar 34 of the spring will at all times exert a forward pressure on the clamping member 27. The forward clamping member 26 is so connected with the lever that the upward movement of the lever will move the clamping member rearwardly and into engagement with the brush. Preferably this connection is established by a link, as shown at 37, this link being provided at its rear end with a bearing portion 38 to enter a slot 39 in a lug 40 extending forwardly from the clamping member 26. At its other end the link is provided with trunnions 41 which are seated in openings in the respective side members of the lever 30. The arrangement of the link is such that when the lever is in its lowermost position, as shown in Fig. 2, the link will extend downwardly and forwardly from its point of connection with the clamping member thus permitting that clamping member to move forwardly until its inner edge is substantially flush with the inner surface of the front wall of the guideway 19. The rear clamping member 27 which is pressed forwardly by the spring 33 will thus force the brush forwardly but will not engage the same with sufficient pressure to materially resist its movement toward the commutator by the spring 21, the forward movement of the clamping member 22 being limited by the contact of the rear end of the slot 28 with the pin 29. Consequently when the lever is in its lowermost position the brush will be held in contact with the commutator by the spring acting on the outer end thereof. When the lever 30 is moved to its upper position, as shown in Fig. 4, the link 37 will be moved into a position in which it extends substantially parallel with said lever. As the forward end of the link moves in an arc described on a radius very much longer than the length of the link 37, it will be obvious that the rear end of the link will be forced rearwardly and will carry the clamping member 26 with it. This movement of the clamping member will cause the same to engage the forward edge of the brush 20, force the brush toward the rear wall of the brush holder and force the rear clamping member 27 rearwardly against the action of the spring 33. Consequently the brush 20 will be gripped between the two clamping members with a pressure which will be sufficient to prevent the inward movement of the brush by the spring 21. It will be apparent that the two clamping members will both engage the brush before they have completed their rearward movement and consequently as the rearward movement of the clamping members is continued they will be elevated by the action of the pins on the inclined slots 28, thereby lifting the brush and firmly holding the same in its lifted position. It will be noted that the arrangement of the lever 30 and link 37 is such as to constitute a toggle and that the action of

the spring 33 on the lever will tend to move this toggle in either direction when it has been once moved past a central position. Consequently after the lever 30 has been 5 positively moved outwardly far enough to carry the toggle across the center the remainder of the movement will be quickly accomplished by the spring, and likewise when the lever has been moved inwardly far 10 enough to carry the toggle across center the inward movement will be quickly completed by the spring.

The automatic control of the brush controlling device may be accomplished in any 15 suitable manner but preferably this operation is controlled by centrifugal force and is therefore controlled by the speed of the motor. As here shown, I have mounted about the motor shaft 2, on the forward side 20 of the plate 8, a second centrifugal device which comprises a series of weights 42 which are preferably segmental in shape. There may be any suitable number of these weights but in the present instance I have 25 employed five weights. This centrifugal device may be connected with the lever of the brush controlling device in various ways but, as here shown, the transverse bar 31 of the lever 30 has the portion 43 extending 30 downwardly and then rearwardly so as to provide a channel between the transverse bar 31 and the part 43, which channel opens rearwardly. Each of the weights 42 has at 35 its outer edge a forwardly extending flange 44, the several flanges extending for the full width of the weights, so that when these weights are in their innermost or retracted positions the flanges 44 of the several weights will constitute a practically continuous circumferential flange, which flange extends 40 into the channel formed between the parts 31 and 43 of the lever 30. It will be obvious therefore that when the centrifugal device moves outwardly from the position 45 shown in Fig. 2 to that shown in Fig. 4 the flange will engage the outer wall of the channel and force the lever outwardly until the toggle has been moved across center. The action of the spring will then carry 50 the lever outward a further distance so as to move the outer wall of the channel away from the flange of the centrifugal device and thus cause both walls of the channel to be spaced from that flange and permitting 55 the latter to run free in the channel without contacting with any part thereof. Likewise when the centrifugal device is retracted the flange 44 will engage the inner wall of the channel and carry the lever inwardly until the toggle is moved across center, and the lever will be moved a further distance by the action of the spring, thereby carrying the inner wall of the channel away 60 from the flange and again spacing the latter from both walls of the channel. This cen-

trifugal device may be assembled on the shaft and its operation controlled in any suitable manner. As here shown, the weights are confined between the plate 8 and an outer retaining plate 45 which fits 70 loosely about the shaft 2 and is retained thereon by a split ring 46 seated in a circumferential groove 47. Each weight has formed therethrough a radial slot 48 and the lugs 15 on the connecting plates 10 are 75 of such a length that they will extend through the slots 48 in the respective weights. The width of the lug is substantially equal to the length of the slots 48 so that these lugs will have no appreciable 80 radial movement with relation to the weights. As here shown, the lugs are provided at their forward outer edges with lips 49 which engage the forward surface of the weights adjacent to the ends of the 85 respective slots. The inner portions of the forward edges of the lugs are substantially flush with the forward surfaces of the respective weights and are engaged by the retaining disk 45. The weights of the second 90 centrifugal device are thus so connected with the contact members or weights of the centrifugally operated short circuiting device that the two devices will move in unison and a single contractile band or spring 95 7 will control the action both of the short circuiting device and of the centrifugally operated mechanism for the brush controlling device. In order that the several 100 weights of the second centrifugal device may move in unison and thus retain the several flanges 44 in circumferential alinement I have so connected these weights one with the other that any movement of one weight will be imparted to all the other weights. 105 In the present device I have rotatably mounted upon the motor shaft 2 a ring or collar 50 having in its peripheral edge a series of notches or recesses 51, corresponding in number to the number of weights. 110 Each weight has an arm 52 rigidly secured thereto, and preferably formed integral therewith, which extends beyond one end of the weight circumferentially of the motor shaft, this arm being of such a character 115 and so arranged that it will extend between the collar 50 and the inner edge of an adjacent weight. Each arm has at that end remote from the weight a projection or nose 53 which enters the corresponding recess in 120 the collar 50 and is capable of a pivotal movement in that recess but is held against circumferential movement with relation to the collar. As will be noted the arrangement is such that when outward movement 125 is imparted to any one of the weights 42 the corresponding arm 52 will cause the collar 50 to rotate about the motor shaft and inasmuch as this collar is connected with all the other weights of this series 130

these weights also are moved outwardly. As a result each weight is held against outward movement until the centrifugal force is sufficient to cause all the weights to move 5 outwardly, and the inward movement of the weights is similarly controlled. Consequently the several weights will be caused to always move at the same time. The several weights 42 are so arranged with relation one to the other that the projections 53 on the several arms will be retained in the respective recesses in the collar 50 during the movement of the weights. As here shown, each weight has in one end thereof 10 a recess 150 and at the other end thereof a projection 151 adapted to extend into the recess 150 of the adjacent weight. The arms 152 extend from and form the lower walls of the recesses 150 and each of these arms 15 has a straight outer edge, as shown at 152, adapted to engage the inner surface of the overlying projection 151. The arrangement is such that when the weights move outwardly by centrifugal force the projections 20 151 will be partially withdrawn from the recess 150 but these projections will maintain contact with the straight portions 152 of the respective arms in all positions of the weights, as is shown in Fig. 3. This contact serves to hold the arm and its projection 30 53 of each weight against outward movement and also serves to hold each weight against tilting movement which might cause the disengagement of the projection 53 from its recess. It will be apparent that when the motor is started the short circuiting device will be retained in its inoperative position and the brush will be held in contact with the commutator until 40 the motor has reached its normal operating speed at which time the centrifugal force developed in the two centrifugal devices will move the same outwardly in unison, the short circuiting element contacting with the commutator bars and short circuiting the latter and the other centrifugal device actuating the brush controlling device to cause 50 that brush to be lifted out of contact with the commutator and retained in that position. The parts will remain in these positions so long as the speed of the motor is maintained but when the motor stops or the speed falls below a predetermined speed the centrifugal devices will be retracted to 55 their initial positions and the brush will be released so that it may be moved into contact with the commutator by the spring 21.

As has been stated, it is not essential that the brush be actually lifted out of contact 60 with the commutator but if it is held against movement toward the commutator the action of the latter will force it out of contact therewith. In Fig. 7 I have shown an arrangement of the brush controlling device 65 whereby this holding or snubbing action

may be attained. In that figure the brush holder is indicated at 54 and the brush 55 is slidably mounted therein and pressed toward the commutator 56 by a spring 57. The brush holder has in one side thereof an opening or slot 58 in which is mounted a brush engaging member or clamping block 59 having an inclined slot 60 through which extends a pin 61. The lever 62 is pivotally mounted at its rear end on the brush holder, as shown at 63, and has its forward portion connected by means of a link 64 with the clamping block 59, the link and the lever being arranged to constitute a toggle. The connection between the link 64 and the lever is a loose one so that the link may have a limited movement with relation to the lever. As here shown, the link is provided with a slot 65 through which the connecting pin 66 extends. A bow spring 67 confined between the connecting pins at the respective ends of the link acts upon the toggle to complete the movement of the lever when it has been moved across center. It will be noted that in the position shown in Fig. 7, the link extends downwardly at an angle to the lever and the inner edge of the clamping block extends but a short distance into the brush holder, the brush being spaced from the rear wall of the brush holder so that the brush is free to move toward the commutator under the influence of the spring 57. When the lever 62 is moved upwardly the action of the toggle forces the clamping block rearwardly, thereby pressing the brush against the rear wall of the guideway and the brush holder and frictionally holding the same against movement under the influence of the spring 57. As has been explained the action of the commutator on the brush will move the 100 same outwardly so that it will have little, if any, contact with the commutator. When the lever is moved inwardly the clamping block will be moved forwardly and the brush released for movement toward the commutator.

In Fig. 8 I have shown a slightly modified form of a device for lifting the brush out of contact with the commutator. The brush holder, brush and commutator are arranged substantially as shown in Fig. 7 but I here employ two clamping blocks or friction members 68 and 69 which are provided with inclined slots 70 through which extend pins 71 and 72 on which the blocks are respectively slidably mounted. The rear block 68 has a rearwardly projecting portion in which is mounted a pin 73 and a spring 74 confined on the pins 73 and 71 tends to move the block 68 forwardly and to press the same against the brush 55. The lever 75 is pivotally mounted at its rear end on the ends of the pin 71 and has its forward portion connected by a link 76 with the forward clamping block 69, the link and the lever constituting 115 120 125 130

a toggle as above described and having substantially the operation of the device in Figs. 1 to 4. In this form of the device also the rear clamping block is normally pressed forward against the brush but the frictional contact is not sufficient to materially restrict the movement of the brush under the influence of the spring 57. The first rearward movement of the forward clamping member 10 69 presses both the brush and the rear clamping block rearwardly so that the brush will be clamped between the two blocks and because of the inclined arrangement of the slots in the blocks will be lifted out of engagement with the commutator.

In Fig. 9 I have shown a different form of connection between the lever and the forward clamping block. In this figure the brush holder, brush, commutator, lever and 20 rear clamping block are substantially the same as shown in Fig. 8 but the forward clamping block 77 is provided in its forward edge with recesses 78 which impart a cam shape thereto, and are engaged by a 25 projection or roller 79 on the lever 75. The action of the spring 74 on the rear block 78 causes this block to press the brush forwardly and the brush presses the forward block against the roller or projection 79. The roller 79 in riding over the projection between the two recesses 78 will force the forward clamping block rearwardly and cause the brush to be clamped between the two blocks. After the roller has passed the projection on 30 the block it will seat itself in the recess and will be retained in this position until pressure is applied thereto. While the clamping blocks will move forward slightly when the roller enters the outer recess this forward 35 movement will not be sufficient to materially decrease the clamping action and the brush will be held as before.

In Fig. 10 I have shown a brush lifting device similar to that shown in Figs. 1 to 4 but have applied the same to a commutator on which the bars are radially arranged on the face of the commutator instead of being arranged peripherally thereof. In that figure the motor shaft is shown at 80, the commutator at 81, the commutator bars at 82, and the brush holder 17, brush 20, lever 30 and clamping blocks 26 and 27 are substantially the same construction and arrangement as shown in Figs. 1 to 4. But the brush holder 50 instead of being radially arranged is arranged substantially parallel with the axis of the motor shaft. A cross bar 31, at what is now the inner end of the lever 30, projects into a circumferential groove 83 in a collar 84 slidably mounted on the motor shaft and forced rearwardly by a spring 85. It will be noted that the groove 83 is of such width that the lever will be maintained 60 at an intermediate position between the walls

of the groove when the brush lifting device 65 is in either position, as has been above described. The collar or sleeve 84 carries a series of short circuiting elements 86 which are brought into line with the commutator bars 82 by the axial movement of the sleeve 70 84, this movement being imparted to the sleeve by a push rod 87 which may be actuated in any suitable manner but is usually operated by a centrifugal mechanism connected with the motor shaft. It will be 75 noted that when the thrust rod moves the sleeve against the tension of the spring 85 it not only brings the short circuiting element into a position to engage the commutator bars but it also actuates the lever 30 80 of the brush lifting device, thus causing the brush to be moved away from the commutator bars.

In Fig. 11 I have shown another mechanism for operating the brush lifting device. 85 The motor shaft is there shown at 88, the commutator at 89, the commutator bars at 90, the brush holder 91 and brush 92 are similar to those above described and clamping blocks 93 and 94 are mounted in the 90 respective side walls of the brush holder. The slots 95 through which the supporting pins 96 extend are so inclined, however, that the clamping blocks will be moved upwardly and forwardly. A lever 97 is pivotally supported on the ends of the pin 96 on the forward side of the brush holder and has its rear portion connected by means of a link 98 with the rear clamping block 93. A spring 99 is connected with the forward 100 clamping block and with the lever and controls the toggle comprising the lever and the link in substantially the manner above described. Extending inwardly from the forward end of the lever is an arm 100, the 105 inner end of which extends into a circumferential groove 101 formed in a collar 102 slidably mounted on the motor shaft 88. Connected with this collar is a thrust rod 103 which may be operated in any suitable 110 manner, as by a centrifugal device connected with the motor shaft. It will be apparent that this push rod will move the collar 102 in one direction or the other and that this movement will cause the lever 97 115 to be moved from one position to the other. The short circuiting device is shown in the form of a series of resilient fingers 104 carried by the collar 102 and so arranged that it can be moved into and out of contact with the commutator bars by the movement of the collar.

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. In a motor comprising a commutator and a brush holder having a stationary guideway, a brush supported in said guideway for movement therein toward and from said commutator, a device movably mounted at one side of said guideway to move said brush laterally in said guideway and hold the same against movement toward said commutator, and centrifugally controlled means to actuate said device.
2. In a motor comprising a commutator and a brush holder having a stationary guideway, a brush supported in said guideway for movement toward and from said commutator, said brush holder having an opening in a side wall of said guideway, a 10 detent mounted for movement in said opening in said brush holder, a device connected with said detent to cause the same to engage said brush and hold the latter against movement toward said commutator, and centrifugally operated means to actuate said device.
3. In a motor comprising a commutator and a brush holder having a stationary guideway, a brush supported in said guideway for movement toward and from said commutator, said brush holder having an opening in a side wall of said guideway, a frictional clamping member mounted for movement in said opening in said brush holder, a device connected with said clamping member to cause the same to engage said brush and press the latter toward the opposite side of said brush holder, and centrifugally operated means for actuating said device.
4. In a motor comprising a commutator and a brush holder having a stationary guideway, a brush supported in said guideway for movement therein toward and from said commutator, a device movably mounted at one side of said guideway to engage said brush and move the same outwardly in said guideway, and centrifugally controlled means to actuate said device.
5. In a motor comprising a brush holder having a stationary guideway, a brush supported in said guideway for movement toward and from said commutator, said brush holder having an opening in a side wall of said guideway, a detent mounted for movement in said opening in said brush holder, a device connected with said detent to cause the same to engage said brush and move the same outwardly and toward that side of said guideway opposite said device, and centrifugally operated means to actuate said device.
6. In a motor comprising a commutator and a brush holder having a stationary guideway, a brush supported in said guideway for movement toward and from said commutator, said brush holder having an opening in a side wall of said guideway, a frictional clamping member mounted for movement in said opening in said brush holder, a device connected with said clamping member to cause the same to engage said brush and press the same toward the opposite side of said brush holder, and centrifugally operated means for actuating said device.
7. In a motor comprising a commutator and a brush holder, a brush supported by said brush holder for movement therein toward and from said commutator, brush engaging members mounted at opposite sides of said brush, yieldable means to press one of said members toward said brush, and centrifugally controlled means to cause the other of said members to engage said brush and move the same against the pressure of the first mentioned means.
8. In a motor comprising a commutator and a brush holder, a brush supported by said brush holder for movement therein toward and from said commutator, brush engaging members mounted on opposite sides of said brush, means to cause said brush engaging members to move upwardly and laterally, a spring acting on one of said members to move the same toward said brush, and centrifugally controlled means to cause the other of said brush engaging members to move said brush and the first mentioned brush engaging member against the action of said spring.
9. In a motor comprising a commutator and a brush holder, a brush supported by said brush holder for movement toward and from said commutator, brush engaging members movably mounted on opposite sides of said brush, means to cause said brush engaging members to move in inclined paths with relation to said brush holder, a spring acting on one of said brush engaging members to move the same toward said brush, and centrifugally controlled means acting on the other of said brush engaging members to move the same toward said brush and away from said commutator, whereby the action of the last mentioned member will cause both brush engaging members and the brush to be moved away from said commutator.
10. In a motor comprising a commutator and a brush holder, a brush supported by said brush holder for movement toward and from said commutator, brush engaging members mounted on opposite sides of the brush for movement with relation one to the other, means for causing said brush engaging members to move in substantially parallel paths diagonal to said brush holder, a spring acting on one of said brush engag-

ing members to move the same toward said brush and toward said commutator, a device for causing the other of said brush engaging members to engage said brush, press 5 the same against the first mentioned brush engaging member and to then move both brush engaging members and said brush away from said commutator, and centrifugally controlled means for actuating said 10 device.

11. In a motor comprising a commutator and a brush holder, a brush supported by said brush holder for movement toward and from said commutator, brush engaging 15 members mounted on opposite sides of said brush for movement with relation one to the other and toward and from said commutator, a spring acting on one of said brush engaging members to move the same toward 20 said brush, a lever extending transversely to said brush holder and pivotally supported near said spring actuated brush engaging member, a connection between said lever and the other brush engaging member to 25 cause the latter to engage said brush and move the same laterally against the pressure of the first mentioned brush engaging member and away from said commutator, and centrifugally controlled means for actuating 30 said lever.

12. In a motor comprising a commutator and a brush holder, a brush supported by said brush holder for movement toward and from said commutator, brush engaging 35 members mounted on opposite sides of said brush for movement with relation one to the other and toward and from said commutator, a spring acting on one of said brush engaging members to move the same toward said brush, a toggle connected with the other brush engaging member to cause the same to engage said brush, and centrifugally controlled means for actuating said toggle.

13. In a motor comprising a commutator 45 and a brush holder, a brush supported by said brush holder for movement therein toward and from said commutator, a member arranged to engage said brush and hold the same against movement toward said commutator, a lever mounted for movement 50 about a fixed axis, a link pivotally connected with said lever and with said brush engaging member, and centrifugally controlled means for actuating said lever.

14. In a motor comprising a commutator and a brush holder, a brush supported by said brush holder for movement toward and from said commutator, said brush holder having slots in the opposite sides thereof, 55 clamping members movably mounted in the respective slots and each having an inclined slot therein, pins extending through the slots in the respective clamping members to guide the same toward and from said commutator, 60 a spring acting on one of said clamping

members to press the same toward the brush, a lever mounted on a fixed axis, a link connecting said lever with the other clamping member, and centrifugally controlled means for actuating said lever.

15. In a motor comprising a commutator and a brush holder, a brush supported by said brush holder for movement toward and from said commutator, said brush holder having slots in the opposite sides thereof, 70 clamping members mounted in the respective slots in said brush holder, each of said clamping members having an inclined slot, pins extending through the slots in the respective clamping members to guide the same, a lever pivotally mounted adjacent to one of said clamping members, a link connecting said lever with the other of said clamping members, a spring acting on the first mentioned clamping member to move 80 the same toward said brush and acting on said lever to hold the same in the position to which it has been moved, and centrifugally controlled means for actuating said lever.

16. In a motor comprising a commutator and a brush holder, a brush supported by said brush holder for movement toward and from said commutator, said brush holder having slots in the opposite sides thereof, a device to engage said brush and hold the same against movement toward said commutator, a lever operatively connected with said device, means to move said lever to the limit of its movement in either direction after initial movement has been imparted thereto, 100 said lever having a channel arranged circumferentially with relation to the axis of said commutator, and a centrifugal device rotatable with said commutator and comprising a part extending into said channel, said part being so arranged that when the centrifugal device moves in either direction said part will engage a wall of said channel and impart initial movement to said lever, and when said part has reached the limit of its movement in said direction, further movement imparted to said lever will move the wall of said channel out of engagement with said part of said centrifugal device.

17. In a motor comprising a commutator and a brush, means to support said brush for movement toward and from said commutator, a device to prevent the movement of said brush toward said commutator, an actuating device for the first mentioned device, a centrifugal device mounted for rotation about the axis of said commutator and comprising a plurality of radially slideable weights, a yieldable device for resisting the outward movement of said weights by centrifugal force, means for connecting said weights one with the other to cause them to move outwardly in unison, and means for operatively connecting said centrifugal de- 110 115 120 125 130

vice with the actuating device for said first mentioned device.

18. In a motor comprising a commutator and a brush controlling mechanism having an actuating member provided with a laterally extending channel, a centrifugal device rotatable with said commutator and comprising a series of radially slidable weights arranged about the axis of said commutator and each having a peripheral flange, the several flanges being arranged in circumferential alinement and extending into the channel of said actuating member, a resilient device to resist the outward movement of said weights, and means to cause said weights to move in unison.

19. In a motor comprising a commutator shaft, a commutator mounted thereon, and brush controlling mechanism comprising an actuating member, a centrifugal device comprising a series of weights arranged circumferentially of said shaft, rotatable therewith and mounted for radial sliding movement, a collar rotatably mounted on said shaft, arms carried by the several weights, extending circumferentially of said shaft and pivotally connected with said collar to cause said collar to move with said weights in both directions, a contractile band to resist the outward movement of said weights, said centrifugal device and said actuating member having cooperating parts to operatively connect the same one to the other.

20. In a motor comprising a commutator shaft, a commutator mounted thereon and a brush controlling mechanism comprising an actuating member, a centrifugal device comprising a series of radially movable weights arranged circumferentially of said shaft and rotatable therewith, a collar rotatably mounted on said shaft and having a circumferentially arranged series of recesses, each of said weights having an arm extending laterally therefrom about said shaft and provided at its end with a part pivotally mounted in one of said recesses, whereby the outward movement of one weight will impart rotatory movement to said collar and thus actuate the other weights, a yieldable device to resist the outward movement of said weights, and means to operatively connect said centrifugal device with said actuating member.

21. In a motor comprising a motor shaft and a commutator mounted thereon and having a circumferentially arranged series of contact bars, a brush lifting device, a short circuiting device for said commutator comprising a series of contact members arranged circumferentially of said shaft and movable by centrifugal force into engagement with said contact bars, a centrifugal device comprising a series of weights mounted about said shaft and rotatable therewith, means for operatively connecting said centrifugal

device with said brush lifting device, and a single contractile band acting upon both said short circuiting device and said centrifugal device to resist the outward movement thereof.

22. In a motor comprising a motor shaft and a commutator carried by said shaft and having a circumferentially arranged series of contact bars, a brush lifting device, a short circuiting device comprising a series of weights arranged circumferentially of said shaft and movable by centrifugal force into engagement with said contact bars, a centrifugal device comprising a series of weights arranged circumferentially of said shaft adjacent to said short circuiting device, said weights being connected with the corresponding contact members of said short circuiting device for radial movement therewith, a contractile band extending about the contact members of said short circuiting device to resist the outward movement of said contact members and of said weights, and means for operatively connecting said centrifugal device with said brush lifting device.

23. In a motor comprising a motor shaft and a commutator carried thereby and comprising a circumferential series of contact bars, a brush lifting device, a centrifugal device operatively connected with said brush lifting device and comprising a series of weights arranged circumferentially of said motor shaft, a short circuiting device comprising a series of contact members arranged circumferentially of said motor shaft between said centrifugal device and said commutator, said contact members being movable by centrifugal force into engagement with the contact bars of said commutator, means for connecting the contact members of said short circuiting device with the weights of said centrifugal device to cause the same to move in unison, and a contractile band extending about said short circuiting device to resist the outward movement thereof and of said centrifugal device.

24. In a motor comprising a motor shaft and a commutator carried thereby and comprising a circumferential series of contact bars, a brush lifting device, a centrifugal device operatively connected with said brush lifting device and comprising a series of weights arranged circumferentially of said motor shaft, a short circuiting device comprising a series of contact members arranged circumferentially of said motor shaft between said centrifugal device and said commutator, said contact members being movable by centrifugal force into engagement with the contact bars of said commutator, means for connecting the contact members of said short circuiting device with the weights of said centrifugal device to cause the same to

move in unison, a contractile band extending about said short circuiting device to resist the outward movement thereof and of said centrifugal device, and an obstruction 5 arranged in the path of said contractile band when the latter is in either its contracted or expanded position.

25. In a motor comprising a motor shaft and a commutator carried thereby and comprising a circumferential series of contact bars, a brush lifting device, a centrifugal device operatively connected with said brush lifting device and comprising a series of weights arranged circumferentially of said motor shaft, a short circuiting device comprising a series of contact members arranged circumferentially of said motor shaft between said centrifugal device and said commutator, said contact members being movable by centrifugal force into engagement with the contact bars of said commutator, means for connecting the contact members of said short circuiting device with the weights of said centrifugal device to cause the same to move in unison, a contractile band extending about said short circuiting device to resist the outward movement thereof and of said centrifugal device, and means for connecting the weights of said centrifugal device one with the other to cause them to move radially in unison.

26. In a motor comprising a motor shaft and a commutator carried thereby and comprising a circumferential series of contact bars, a brush lifting device, a centrifugal device operatively connected with said brush lifting device and comprising a series of weights arranged circumferentially of said
35 motor shaft, each of said weights having an opening therethrough, a short circuiting device comprising a series of contact members arranged circumferentially of said shaft between said centrifugal device and said
40 commutator, a series of connecting members interposed between the contact members of said short circuiting device to divide the same into groups, each of said connecting members having a part seated in the
45 opening of the adjacent weight of said centrifugal device and held against movement relatively thereto, and a yieldable member
50 acting on said weights and said connecting members to resist the outward movement thereof.
55

27. In a motor comprising a motor shaft and a commutator carried thereby and comprising a circumferential series of contact bars, a brush lifting device, a centrifugal device operatively connected with said brush lifting device and comprising a series of

weights arranged circumferentially of said motor shaft, each of said weights having an opening therethrough, a short circuiting device comprising a series of contact members arranged circumferentially of said shaft between said centrifugal device and said commutator, a plurality of connecting plates arranged in pairs and interposed at intervals between the contact members of said short circuiting device, the connecting plates of each pair having oppositely extending portions to form seats for the inner ends of said contact members, the connecting plates of each pair having projections extending through the openings in the adjacent weights of said centrifugal device to hold the same against movement relatively thereto, and a contractile band extending about said short circuiting device and engaging said contact members and said connecting plates to resist the outward movement thereof.

28. In a motor comprising a motor shaft and a commutator carried thereby and comprising a circumferential series of contact bars, a brush lifting device, a centrifugal device operatively connected with said brush lifting device and comprising a series of weights arranged circumferentially of said motor shaft, each of said weights having an opening therethrough, a short circuiting device comprising a series of contact members arranged circumferentially of said shaft between said centrifugal device and said commutator, a plurality of connecting plates arranged in pairs and interposed at intervals between the contact members of said short circuiting device, the connecting plates of each pair having oppositely extending portions to form seats for the inner ends of said contact members, the connecting plates of each pair having projections extending through the openings in the adjacent weights of said centrifugal device to hold the same against movement relatively thereto, a contractile band extending about said short circuiting device and engaging said contact members and said connecting plates to resist the outward movement thereof, a disk mounted about said shaft between said short circuiting device and said centrifugal device and having radial slots through which the projections on said connecting plates extend, said disk having an annular rib arranged to engage said contractile band and resist its movement when it is in either its contracted or expanded position.

In testimony whereof, I affix my signature hereto. 120

GEORGE H. LELAND.
